DESIGN FOR A COMBINED SWITCH LEVER GUARD AND ACTUATOR

Alvin W. Krieger, Milwaukee, Wis., assignor to
Cutler-Hammer, Inc., Milwaukee, Wis., a cor-
poration of Delaware

Application April 20, 1942, Serial No. 106,633

Term of patent 14 years

To all whom it may concern:

Be it known that I, Alvin W. Krieger, a citizen of the United States and a resident of Milwaukee, in the county of Milwaukee and State of Wisconsin, have invented a new, original, and ornamental Design for a Combined Switch Lever Guard and Actuator, of which the following is a specification, reference being had to the accompanying drawing, forming part thereof.

Figure 1 is a perspective view of a combined switch lever guard and actuator in one position thereof, showing my new design.

Fig. 2 is a rear elevational view thereof.

Fig. 3 is a top plan view of said combined guard and actuator.

Fig. 4 is a front elevational view thereof.

Fig. 5 is a side elevational view thereof.

Fig. 6 is a view similar to Fig. 5, but showing said combined guard and actuator in another position thereof.

I claim:

The ornamental design for a combined switch lever guard and actuator, substantially as shown.

ALVIN W. KRIEGER.
